E. W. NIELSEN

RADIO TELEPHONE RECEIVER

Filed May 25, 1922

INVENTOR
Einar W. Nielsen
BY
Ferd C. Fischer.
ATTORNEY

UNITED STATES PATENT OFFICE.

EINAR W. NIELSEN, OF NEWARK, NEW JERSEY.

RADIO TELEPHONE RECEIVER.

Application filed May 25, 1922. Serial No. 563,562.

To all whom it may concern:

Be it known that I, EINAR W. NIELSEN, a citizen of the United States, residing at Newark, in the county of Essex and State of New Jersey, have invented new and useful Improvements in Radio Telephone Receivers, of which the following is a specification.

One object of the invention is to provide 10 a particularly sensitive receiver suited for aerial or radio work, compact and conveniently handled without danger of disarrangement.

Another purpose is in the provision of a 15 novel and effective type of magnet by which superior results are attained.

These and other like aims, such as simplicity, durability and neatness of appearance are attained by the novel construction, 20 combination and arrangement of parts hereinafter described and shown in the accompanying drawing forming a material part of this disclosure, and in which:

Figure 1 is a top plan view of an embodiment of the invention, parts being broken away to show the interior.

Figure 2 is a transverse sectional view taken in a plane indicated by the line 2—2 of Fig. 1.

Figure 3 is a fragmentary sectional view taken on line 3—3 of Fig. 1.

Figure 4 is a side elevational view of one of the cores showing its initial winding and heads.

Figure 5 is a perspective view of the magnet drawn to a reduced scale.

The receiver casing is of conventional form, convenient size and made of usual non-conducting material, the same comprising 40 a cylindrical cup having a flat base or bottom wall 10 and side wall 11 formed with a reduced screw-threaded upper portion 12.

Connecting by the screw-thread is the 45 flanged portion 13 of a cup 14 having a concave outer surface 15 and containing a central opening 16.

An annular seat 7, on the inner side of 50 the cup, registers with the top of the cup and clamped firmly at its edge therebetween is a diaphragm or membrane 18 which acts as the armature of the magnet later described.

Resting on the level inner surface of the 55 bottom 10 of the cup is a circular plate 19 of insulating material as fibre, cardboard,

etc. and mounted therein is a disc 20 of chromium steel, slightly less in diameter than the plate 19 but of considerable thickness preferably approximating one fifth of the depth of the cup chamber, and constituting the base element of a magnet.

Said disc 20 contains two circular openings 21 and 21' spaced a predetermined distance apart on its center line and between these holes is a longitudinal slot 22 extending at a right angle to the plane of the openings 21—21' and terminating in circular enlargements 23 and 23' at its ends.

The pole pieces of cores 24 and 24' of the 70 magnet may be of soft iron in the form of round posts, reduced at one end, as at 25, to fit the openings 21 into which they are securely riveted bringing the shouldered enlarged portion into rigid engagement with the surface of the magnet 20.

Fixed to the magnet cores 24—24' at points slightly below their free upper ends, and also at their bottom to rest on the disc, 80 are fibre washers 26 constituting spool ends between which the wires are coiled which energize the magnet.

The first or inner coils 27 on each core are wound from independent bare wires and overlaid by coils of the same wire insulated 85 in the usual manner, to the full diameter of the spools 28 and 28', the outer extending ends 29 and 29' of the magnet coils being engaged with separate connections as shown in Figure 1 and further described.

It is to be noted that the bare inner coils are directly grounded on the cores 24 and 24', which are in electrical connection with each other by reason of the plate 20 in which they are fixed, and which forms part 95 of the circuit.

Said connections consist of a pair of insulating bushings 30 passed through openings appropriately formed in the cup bottom 10 and plate 19, and thence through the openings 23—23' in the magnet 20, the length of the bushings being slightly less than the combined thicknesses of these several elements.

Passing through the bushings 30 are 105 screws 31 formed with or fixed in binding posts 32, the same being provided with means for securing lead wires as usual.

Pairs of insulating washers 33 and 34 are used in connection with these screws, the same seating respectively on the outer surface of the wall 10 and the exposed surface 110

of the magnet base 20, these washers being clamped firmly in position by the nuts 35.

The inner extending ends of the screws 31 are formed conically, as at 36 and slit or bifurcated as at 37 presenting wedge-shaped openings in which are engaged the ends of the wires 29—29' leading from the respective coils 28—28'.

From the foregoing it will be seen that 10 each pole of the magnet is directly connected to its corresponding binding post independently, that the magnet base is circular and of relatively hard material and that provision is made therein for the lines of force 15 by the slot 22, forming a novel and effective device of unusual sensitiveness.

Although the improvements have been described with considerable detail, it is not desired to be limited exactly thereto since 20 changes and modifications may well be made without departing from the spirit and scope of the invention in its broadest aspect.

Having thus described my invention, what I claim as new and desire to secure by Letters Patent, is:—

1. A receiver of the type described comprising a shallow cup shaped casing having a flat bottom, a cover engaged therewith both casing and cover being composed of 30 dielectric material, a diaphragm clamped between said cup and cover, an insulating disc in the bottom of said cup, a circular magnet seated on said disc, a pair of cores fixed in said magnet, a bare wire wound helically on each core, insulated continuations of said wire coiled thereover, and insulated binding posts extending through the bottom of said cup, disc and magnet, said posts being cleft at the inner ends presenting V-shaped openings to engage the terminal wires from one of said core windings.

2. A radio telephone receiver comprising a shallow, flat-bottomed cup, a cover removably engaged therewith, both casing and cover being composed of dielectric material, a diaphragm clamped between the edges of said cup and cover, an insulated disc of chromium steel fixed in said cup forming the base element of a magnet, pole pieces fixed 50 in spaced relation at the center of said disc, said pole pieces extending adjacent said diaphragm, independent insulated wires coiled on said pole pieces, insulating bushings passing through said cup and disc, binding posts having stems encased in said bushings, means on the stems for clamping said bushings, said bushings being diametrically opposed to said pole pieces, and cones at the inner ends of the stems sharply cleft to frictionally engage with the terminals of the respective windings by frictional contact only.

3. In a radio telephone receiver, the com-

bination with a cup, a cover and a diaphragm clamped therebetween, of a magnet 65 comprising a circular disc of steel having an elongated slot passing through its center leading to circular openings at its end, a pair of iron cores fixed on opposite sides of the slot at the center, windings on said cores, a 70 pair of binding posts, insulated bushings, fixed in said cup and passing through the openings in said disc through which said posts pass, and a conical inner end on each post having a wedge shaped slot to receive 75 the terminal wires from each winding.

4. In a radio telephone receiver, the combination with a cup, a cover and a diaphragm clamped therebetween, of a magnet comprising a circular insulated steel disc 80 substantially fitting the interior of said cup and held to the bottom thereof, said disc having an elongated open slot, a pair of iron cores riveted to said disc one on each side of the slot, insulating bushings at the 85 ends of the slot, said bushings passing through the bottom of said cup, screw threaded stems passing through said bushings, means on said stems for engaging said bushings in fixed position, binding posts on the 90 outer ends of said stems, connecting elements on the inner ends thereof, and windings on said cores having their outer terminals engaged in said connections.

5. A fixed field magnet of circular shape 95 having an elongated open slot passing through its center, and a pair of electro-magnet elements fixed on said field magnet upon opposite sides of the slot therein.

6. A fixed field magnet of circular shape 100 having an elongated open slot passing through its center, a pair of electro-magnet elements fixed on said field magnet upon opposite sides of the slot therein, and a binding post associated with each electro-magnet 105 element.

7. In a radio telephone receiver, the combination with a cup having a cover and a diaphragm clamped therebetween, of a magnet comprising a steel base fixed in said cup, 110 a pair of iron cores in electrical engagement with said base, a coil of insulated wire wound on each core, the innermost winding being grounded on the cores, a pair of binding posts adjustably mounted in said cup 115 to extend through the bottom thereof, said binding posts having conical ends containing wedge shaped recesses, and connections between the outer windings of said coils and the recesses in the cores binding posts. 120

This specification signed and witnessed this 20th day of May, 1922.
